UNITED STATES PATENT OFFICE.

GEORGE W. THOMPSON, OF SAG HARBOR, NEW YORK.

DESIGN FOR A MUSTACHE-SPOON.

SPECIFICATION forming part of Design No. 19,926, dated June 24, 1890.

Application filed May 16, 1890. Serial No. 352,095. Term of patent 14 years.

To all whom it may concern:

Be it known that I, GEORGE W. THOMPSON, a citizen of the United States, and a resident of Sag Harbor, in the county of Suffolk and State 5 of New York, have invented certain new and useful Improvements in Designs for Mustache-Spoons; and I do declare the following to be a full, clear, and exact description of the invention, such as will enable others skilled 10 in the art to which it appertains to make and use the same, reference being had to the accompanying drawings, and to letters of reference marked thereon, which form a part of this specification.

15 Figure 1 of the drawings is a representation of a perspective view of a mustache-spoon showing my design. Fig. 2 is a plan view; and Fig. 3 is a side and 4 is an end view.

The invention relates to a new and original 20 design for mustache-guard spoons; and it consists in the novel form and configuration thereof, as shown and described.

The leading feature of my design consists 25 in a raised convex guard-bridge A, extending from end to end of the spoon-bowl B and over one-half of said spoon-bowl, as shown, its inner and lower edge a extending from the junction b of the bowl with the handle to the more acutely-rounded end c of the bowl,

while the outer portion joins the bowl for a 30 distance at each end, as indicated at d and e, and is free between those portions and raised in convex form, as at g. Below this free portion the bowl of the spoon is formed with a depressed concave projecting lip h, dipping 35 in curved form, as shown, below the general level of the edge of the bowl, providing an opening at k of elongated form and facing obliquely outward and upward. The inner longitudinal margin of the bridge portion is 40 usually provided on its upper surface with a slight raised rib, as illustrated at l.

What I claim is—

The design for a mustache-spoon, consisting of the bowl having the longitudinal convex bridge, covering one-half thereof, and having at one side an inward-curved or concave portion uniting with a downward-curved or concave surface in the side of said bowl, to represent an elliptical opening with a lower 45 forwardly or outwardly projecting edge, as 50 shown.

In testimony whereof I affix my signature in presence of two witnesses.

GEORGE W. THOMPSON.
